UNITED STATES PATENT OFFICE

166,053

COMBINED SLIPPER AND SOCK

Louis M. Spack, Englewood, N. J., assignor to
Utilitron Incorporated, Hoboken, N. J., a corporation of New York

Application August 16, 1951, Serial No. 16,299

Term of patent 7 years

(Cl. D47—7)

To all whom it may concern:

Be it known that I, Louis M. Spack, a citizen of the United States of America and resident of Englewood, in the county of Bergen and State of New Jersey, have invented a new, original, and ornamental Design for Combined Slipper and Sock, of which the following is a specification, reference being had to the accompanying drawing, forming part hereof, in which:

Fig. 1 is a perspective front view of a combined slipper and sock, showing my new design;

Fig. 2 is a perspective rear view of the same; and

Fig. 3 is a fragmentary plan view, on an enlarged scale for bringing out more clearly the details of the type of trim used by applicant on his combined slipper and sock.

I claim:

The ornamental design for a combined slipper and sock, as shown and described.

LOUIS M. SPACK.
